UNITED STATES PATENT OFFICE.

ISAAC LEONARD HARRIS, OF JACKSONVILLE, FLORIDA.

ACETYLENE-GAS GENERATOR.

SPECIFICATION forming part of Letters Patent No. 655,487, dated August 7, 1900.

Application filed June 8, 1900. Serial No. 19,582. (No model.)

To all whom it may concern:

Be it known that I, ISAAC LEONARD HARRIS, a citizen of the United States, residing at Jacksonville, in the county of Duval and State of Florida, have invented certain new and useful Improvements in Acetylene-Gas Generators, of which the following is a specification.

My present invention relates to improvements in the feeding device of my Letters Patent No. 637,252, dated November 21, 1899, and my application for Letters Patent filed January 29, 1900, Serial No. 3,086.

In the accompanying drawings, Figure 1 is a general view of a gas-generator, partly in section, showing my improvements on line A B. Fig. 2 is a similar view at right angles to Fig. 1 and showing my improvements on line C D. Fig. 3 is an enlarged side view of my improved hanging-strips with pulleys attached. Fig. 4 is a front view of Fig. 3. Fig. 5 is an enlarged interior view of the barrel and disks on the motor-shaft for moving the improved chain-belt floor. Fig. 6 is a cross-section of same, showing channel-guides in which one of the disks is confined. Fig. 7 is a piece of the chain-belt floor laid flat, showing the fastening links and pins on the under side; and Fig. 8 is a larger view of one link for fastening the flat plates of the chain belt together.

Similar figures refer to similar parts in the several views.

Features already patented and shown in my former application are referred to by letters.

a is the gasometer-casing, and b the gasometer-bell, through the middle of which stands the carbid-chamber c. At the bottom of the carbid-chamber c is located the mechanism for discharging the carbid into the water-tank d. This mechanism is the immediate subject of my present application and consists of three or more hanging-strips 1, extending across the full width of the opening into the water-tank at the bottom of the carbid-chamber working loosely side by side on a fixed pin 2, each hanging-strip having a small roller-pulley 3, working on an idle axle-pin 4, near its bottom edge, in suitably-arranged wire journals 5, fastened to the hanging-strips, (shown in Figs. 3 and 4,) and an

endless-chain-belt moving floor 6, operated by two disks 7, composing the two ends of a barrel-drum 8, fastened securely to the motor-shaft M.

In my former applications I considered it expedient to operate the chain-belt moving floor by means of sprocket-wheels. These sprocket-wheels necessitated openings in the floor of the chain to receive the sprockets. Experiment has proved that sprocket-wheels are entirely unnecessary and that plain disk pulleys fastened to a motor-shaft develop sufficient friction when the chain belt envelops the disks to the extent shown on my drawings to operate it and to discharge carbid into the water-tank as effectually as the former methods; but sprocket-wheels also served to guide the belt uniformly in its travel, and their absence must be compensated for in this respect. This is accomplished by the channel-guides 9, consisting of narrow flat strips of metal soldered to the under side of the plates composing the chain belt 6 in two parallel rows opposite to each other, with their meeting ends bent outward, as shown in Fig. 5, and just far enough apart to admit one of the disks 7 to pass between them. One such channel is sufficient for the guidance of the belt. The chain belt 6, composed of transverse flat plates, is held together by pins 10, soldered near the edge of each joint, each pair of pins being secured by a link 11, Fig. 8. There are two links to each joint. The chain belt 6 also passes over two smaller disks 12, composing the two ends of a barrel-drum which is fastened on an idle shaft 13. The descending convex surface of the chain belt 6 comes into frictional contact with the pulleys 3, fastened to the hanging-strips 1, as shown in Fig. 3, and when carbid is discharged into the water-tank d the pulleys 3 are pushed away from the chain belt by the carbid in its passage over the descending part of the belt. Thus the carbid falls into the water-tank d from between two revolving surfaces.

The motive power which operates the mechanism of the carbid-feed through the medium of the shaft M is derived from the weight W, Fig. 2, which is fully treated of in my said Letters Patent No. 637,252, dated November 21, 1899, and my application for Letters Pat-

ent filed January 29, 1900, Serial No. 3,086. A detailed explanation of the operation of an entire acetylene-gas generator is therefore unnecessary.

5 Having thus described the nature of my invention, what I claim as new, and desire to secure by Letters Patent, is—

1. In an acetylene-gas generator in combination with a water-tank and a carbid-chamber, the hanging-strips 1 and the roller-pulleys 3 fastened thereto and working idly near the lower extremity of said hanging-strips and forming a part thereof for controlling the carbid in its delivery into the water-tank, 15 said hanging-strips working loosely side by side on the fixed round bar 2 in sufficient numbers to extend across the full width of the opening into the water-tank at the bottom of the carbid-chamber substantially as shown.
- 20 2. In an acetylene-gas generator in combination with a water-tank and a carbid-cham-

ber, the chain belt moving floor 6 for feeding the carbid into the water-tank, said chain belt comprising an endless series of transverse plates, the pins 10 fastened to the under side of the plates, the links 11 encompassing each pair of pins and holding the plates together in an endless belt, the channel-strips 9 fastened to the under side of the plates 6 with their meeting ends bent outward in two 30 parallel rows, the two disks 7 fastened to a motor-shaft for operating said belt, one of said disks working in the channel formed by the parallel strips 9 for the purpose of guiding the belt uniformly, the small disks 12 and the idle shaft 13 to which said disks are fastened and over which the chain belt works loosely substantially as shown and described.

ISAAC LEONARD HARRIS.
